DRAWER SLIDE

Howard L. Kennedy and Charles A. Uncapher,
Van Wert, Ohio, assignors to Kennedy Manufacturing Company, Van Wert, Ohio, a corporation of Indiana

Application May 2, 1941, Serial No. 391,506

2 Claims. (Cl. 45—77)

This invention relates to slide suspensions for drawers, trays and the like which are slidably mounted in a supporting structure, such as a cabinet, tool chest, or desk, and is an improvement upon the device disclosed in the copending application of Howard L. Kennedy, Serial No. 370,211, filed December 14, 1940. In the copending application retractable stops are provided in the slide bar which have the form of elongated resilient metal strips anchored at one end to the bar and provided with projecting portions adjacent and free ends which normally lie in the path of fixed stops on the members in which the slide bar is mounted.

The present invention has for its object to provide a releasable stop device of the type disclosed in the earlier application in which the releasable stop will not be disengaged by violent impacts, and in which the impacts of the cooperating stops against the releasable stop members are transmitted directly to the slide bar, thereby protecting the anchoring connection between the strips and the slide bar against tension stresses.

With the above and other objects in view the invention may be said to comprise the device illustrated in the accompanying drawing herein-after described and particularly set forth in the appended claims, together with such variations and modifications thereof as will be apparent to one skilled in the art to which the invention pertains.

Reference should be had to the accompanying drawing forming a part of this specification, in which:

Figure 1 is a perspective view showing the invention applied to the drawer of a cabinet or the like.

Fig. 2 is a perspective view of the suspension members detached from the drawer and supporting structure.

Fig. 3 is a section taken on the line indicated at 3—3 in Fig. 2.

Fig. 4 is a fragmentary top plan view of the suspension member shown in Fig. 2, and

Fig. 5 is a fragmentary longitudinal section through the suspension members on a somewhat enlarged scale.

In Fig. 1 of the accompanying drawing there is shown a housing or cabinet 1, a drawer 2 and one of two identical drawer supporting or suspension devices which are interposed between the sides of the drawer and the adjacent walls of the cabinet.

The suspension device comprises two support-

ing members in the form of channel bars 3 and 4 which are secured in fixed position to the drawer 2 and the wall of the cabinet, with the open side of one supporting bar facing the open side of the other. A supporting slide bar 5 is mounted in the two channel bars 3 and 4 for end-wise movement therein, the channel bars and slide bars providing an extensible support for the drawer 2. The channel bars 3 and 4 are provided with inwardly bent side flanges 6 which provide retaining grooves and each of the channel bars is provided with a stop 7 in the channel thereof which may be formed by striking up an integral projection from the web of the bar. The slide bar 5 is preferably formed of sheet metal and may consist of two channel shaped members 8 and 9 attached together back to back and provided with edge flanges 10 which slide in the grooves provided by the flanges 6 of the supporting bars. The slide bar is provided with an opening 11 adjacent each end thereof through the webs of the channel members 8 and 9 and releasable stop members are mounted in the channels on opposite sides of the bar 5 for engagement with the stops 7 which project into the channels of the slide bar. Two releasable stops are provided on the slide bar, one mounted in each channel thereof and one at each end of the bar 5.

The releasable stop members are of identical construction and each comprises an elongated resilient metal strip 12 anchored at its inner end in a socket 13 provided in the slide bar inwardly of one of the openings 11 and bowed sufficiently to hold the free end thereof against the slide bar with spring pressure. Each strip 12 extends outwardly from its anchoring socket 13 past an opening 11 to adjacent an end of the slide bar. The outer end of each strip is free for movement toward or away from the face of the slide bar and is doubled back upon itself to provide a finger tab 14 in the form of a loop which is yieldingly held against the face of the bar outwardly of the opening 11. The end of the doubled back portion of the strip 12 which is on the inner side of the strip is bent laterally to provide a stop flange 15 which projects through the opening 11 into the path of a stop member 7.

The two stop members 7 are disposed between the stop flanges 15 of the two releasable stop members so that the sliding movement of the slide bar with respect to each of the supporting bars 3 and 4 is limited. The stop flange 15 of each releasable stop member is disposed in its opening 11 with its outer face closely adjacent

the outer edge of the opening 11, so that said edge of the opening provides an abutment for the stop flange which takes the impact of the stop 7 when the stop engages the flange, so that the strip 12 is not subjected to tension when engaged by the stop and the connection of the strip to the slide bar at the anchoring socket 13 need not be a strong connection since the anchor is not required to resist the impact of the stop members.

The edge of the opening 11 engaged by the stop flange 15 also serves as a fulcrum for the stop flange so that the rocking movements of the stop flange under the pressure of the stop 7 does not tend to dislodge the stop flange from engaging position. The loop 14 and the bowed portion of the strip 12 provide a resilient support for the flange 15 which permits the flange to rock upon the edge of the opening 11 under the pressure of the stop 7 to cushion the impact of the stop. The rocking of the flange 15 on the slide bar tilts the loop 14 outwardly tending to open the loop and increase the bow in the body of the strip 12. The resistance of the opening metal strip to such distortion effectively cushions the angular movements of the stop flange. The pressure of the stop 7 against the flange 15 may force the flange to or past a perpendicular position with respect to the slide bar, so that the pressure of the flange against the edge of the opening tends to lock the flange in engaging position rather than to force the flange outwardly through the opening.

Whenever it is desired to remove the drawer entirely from the cabinet, one of the releasable stops may be shifted out of stop engaging position by means of the projecting loop 14, so that the slide bar may be freed from one of the supporting members. In replacing the drawer on the supporting members, the inclined faces of the stop member 7 will force the releasable stop member outwardly until the stop member 7 is moved to a position within the stop flange, after which the strip 11 will spring inwardly toward the face of the slide bar to return the stop flange to engaging position.

It is to be understood that variations and modifications of the specific devices herein shown and described for purposes of illustration, may be made without departing from the spirit of the invention.

What we claim is:

1. A slide suspension comprising a supporting member having a channel, a stop carried by the supporting member in said channel, a slide bar

mounted for endwise sliding movement in said channel, said slide bar having a longitudinal channel into which said stop projects and an opening to said channel, and a releasable stop member carried by the slide bar, said releasable stop member comprising an elongated resilient metal strip disposed longitudinally of the bar and having its inner end anchored to said bar at a point spaced from said opening and to the same side 10 of said opening as said stop, the outer end portion of the releasable stop member being free and extending across said opening, the free end of said strip being doubled back upon the side facing the opening to provide a finger tab in the form of a loop outwardly of the opening, the end of the strip being bent laterally to provide a resilient stop flange inwardly of the tab which projects through said opening into the path of said stop, the outer face of said stop flange being closely 15 adjacent the outer edge of said opening, whereby 20 said edge of the opening provides an abutment and fulcrum for said stop flange.

2. A slide suspension comprising two channel-shaped supporting members disposed with the 25 open side of one facing the open side of the other, a stop carried by each supporting member in the channel thereof, a slide bar having opposite side portions slidably mounted in said channels, said slide bar having longitudinal channels in opposite 30 side faces thereof to receive said stops, and having an opening adjacent each end through the portion of the bar separating the channels in opposite faces thereof, and releasable stop members carried by the bar and engageable with said 35 stops, said releasable stop members each comprising an elongated strip of resilient metal, one mounted in each of said channels of the bar and each anchored at its inner end to said bar, the free ends of said strips extending past said openings and being doubled back upon the body of the strip on the side thereof facing the bar to provide a finger tab in the form of a loop outwardly of the opening, the end of the doubled-back portion being bent laterally to provide a stop 40 flange inwardly of the tab which projects through the adjacent opening into the path of one of said 45 stops, the stop flange of each releasable stop member being closely adjacent the outer edge of the opening through which it projects, 50 whereby said edge of the opening provides an abutment and fulcrum for said stop flange.

HOWARD L. KENNEDY.
